DESIGN FOR A KITCHEN RANGE

Max Richard Lehman, Quincy, Ill., assignor to
Dixie Foundry Company, Inc., Cleveland, Tenn.,
a corporation of Delaware

Application May 18, 1939, Serial No. 85,072

Term of patent 3½ years

To all whom it may concern:

Be it known that I, Max Richard Lehman, a citizen of the United States of America, residing at Quincy, in the county of Adams and State of Illinois, have invented a new, original, and ornamental Design for a Kitchen Range, of which the following is a specification, reference being had to the accompanying drawing, forming a part thereof.

In the drawing:

The figure is a perspective view of a kitchen range showing my new design.

The side of the range not illustrated is substantially like the side shown.

I claim:

The ornamental design for a kitchen range, as shown and described.

MAX RICHARD LEHMAN.
